UNITED STATES PATENT OFFICE.

GEORGE F. CONNER, OF PORT HURON, MICHIGAN.

DESIGN FOR A TRACTION-WHEEL.

SPECIFICATION forming part of Design No. 32,457, dated April 3, 1900.

Application filed March 9, 1900. Serial No. 8,079. Term of patent 14 years.

To all whom it may concern:

Be it known that I, GEORGE F. CONNER, a citizen of the United States, residing at Port Huron, in the county of St. Clair and State 5 of Michigan, have invented and produced a new and original Design for Traction-Wheels, of which the following is a specification, reference being had to the accompanying drawings, forming a part thereof.

10 This invention relates to an original design for traction-wheels as is embodied in the configuration and shape of the rim portion thereof, as presently to be described and shown in the drawings.

15 In the drawings, Figure 1 shows a traction-wheel embodying the design in perspective. Fig. 2 is a face view of a portion of the periphery. Fig. 3 is a side view of the same.

In the drawings, A designates the hub, and 20 B the suspension-spokes, of the ordinary type. C designates the rim, which constitutes the

essential feature of this invention. This rim has a series of transverse ribs on its outer face, spaced apart at an equal distance, and between the ribs is a surface having a concaved face. The curvature of the face of the periphery between the ribs is substantially the same transversely. The under side of the periphery of the rim is curved, as shown. 25

The essential feature of the design, as stated above, resides in the peculiar shape of the rim.

Having thus described the invention, what I claim as new, and desire to secure by Letters Patent, is—

The design for a traction-wheel substantially as shown and described. 35

In testimony whereof I affix my signature in presence of two witnesses.

GEORGE F. CONNER.
